UNITED STATES PATENT OFFICE

CHARLES A. OLSON, OF GENEVA, ILLINOIS, ASSIGNOR TO CRANE CO., OF CHICAGO,
ILLINOIS, A CORPORATION OF ILLINOIS

DESIGN FOR A COMBINED HUMIDIFIER AND RADIATOR COVER

Application filed October 2, 1931. Serial No. 41,298. Term of patent 14 years.

To all whom it may concern:

Be it known that I, CHARLES A. OLSON, citizen of the United States, residing at Geneva, in the county of Kane and State of Illinois, whose post-office address is 728 Shady Avenue, Geneva, Illinois, has invented a new, original, and ornamental Design for a Combined Humidifier and Radiator Cover, of which the following is a specification, reference being had to the accompanying drawings, forming part thereof.

In the drawings:

Fig. 1 is a front view of the combined radiator and humidifier cover embodying my design.

Fig. 2 is an end elevation of the combined radiator and humidifier cover.

Fig. 3 is a view showing a top view with the lid in open position.

Fig. 4 is a section taken on the front corner in Fig. 1.

Fig. 5 is a section taken on the rear side corner in Fig. 2.

I claim:

The ornamental design for a combined humidifier and radiator cover substantially as shown and described.

CHARLES A. OLSON.
